UNITED STATES PATENT OFFICE.

CHARLES FREDRICK SCHILLING, OF LACOMBE, ALBERTA, CANADA.

GRATE.

1,359,111.

Specification of Letters Patent. Patented Nov. 16, 1920.

Application filed May 28, 1917. Serial No. 171,532.

To all whom it may concern:

Be it known that I, CHARLES F. SCHILLING, a subject of the King of Great Britain, and resident of Lacombe, in the Province 5 of Alberta, Dominion of Canada, have invented certain new and useful Improvements in Grates, of which the following is a specification.

This invention relates to improvements in 10 grates, particularly adapted for use in boiler furnaces and the like, and the objects of the invention are to facilitate delivering air from the center of the fire radially or laterally to the outside thereof, to permit 15 of the draft being readily controlled, to simplify the arrangement of the grate bars, and generally to adapt the several parts to better perform the functions required of them.

With the above and other objects in view, 20 the invention consists essentially of the improved construction particularly described and set forth in the accompanying specification and drawings forming part of the 25 same.

In the drawings:

Figure 1 is a longitudinal section through 30 the front plate of a boiler and showing the vertical grate bars in lowered position, the dotted lines indicating vertical grate bars when elevated,

Fig. 2 is a plan view of the stationary 35 grate bars and the vertical movable grate bars.

Fig. 3 is an enlarged longitudinal section through the front plate of the boiler and showing a vertical grate bar in the furnace, the bar being broken intermediate of the length and in lowered position.

Fig. 4 is a side elevation partly sectional 40 of an elevating rack and its coacting pinion.

Fig. 5 is a vertical section of a guide 45 designed to carry the elevating rack and its coacting pinion.

Fig. 6 is an enlarged vertical section of 50 one of the bars constituting the vertical grate.

Fig. 7 is a perspective view of the improved grate as seen in position in a boiler 55 setting.

Fig. 8 is a fragmentary perspective view 60 of the stationary grate bars, showing the

guides located between the same to carry the movable grate bars.

Like characters of reference refer to like 55 parts in the several figures.

In the drawings, B represents a portion 60 of a boiler setting of any usual description having a grate provided with a plurality of removable grate bars 28, with which a 65 plurality of equidistantly spaced vertically movable grate bars 29 coact.

The bars 28 may be removably supported 70 in any known manner for replacement. The grate bars 28 constitute the horizontal 65 grate and are adapted to operatively support a plurality of guides 30 arranged in pairs, one at each end of the grate bars 28, the said guides being embraced by adjacent pairs of bars 28, and being held from vertical displacement by a flange 31 formed 75 along the lateral edges of the guides and engaging with the upper face of the grate bars 28, while the curvilinear projection 32 located below each grate bar 28 engages 80 with the lower face thereof, and assists in securing the guides in the desired position.

Slidably mounted in each guide 30 is a rack 33 provided at the upper end with a square orifice 34 with which the lug 35 of 85 a vertical grate bar 29 engages, the said rack meshing with the pinion 36 carried by the spindle 37 which is journaled in the curvilinear projection 32 of the guide 30 and extends through the front of the boiler 85 plate 38, where it is provided with a crank handle 39 which permits of the spindle 37 being manually rotated.

Each vertical grate bar 29 consists of a 90 vertically disposed bar 40 formed integral with and depending from the longitudinally extending bar 41, the bar 40 having a central longitudinally extending recessed portion and being provided with slots 42 in the lateral wall, through which slots air is 95 designed to be delivered to the grate.

It is desirable that all the grate bars 29 should be capable of simultaneous vertical movement, and to this end I provide each of the spindles 37 with a pinion 43, adapted 100 to mesh with the rack 44 slidably mounted in the bracket 45 secured to and extending transversely across the front plate 38 of the boiler.

It will be understood that only one of the spindles 37 is provided with a crank handle 39, and (when rotated) motion is transmitted to the pinion 43 which moves the rack 44 in a longitudinal direction, transmitting motion to the several pinions 43 and simultaneously actuating all the grate bars 29.

The assembly of the grates will be readily understood from the foregoing description.

10 When this type of grate is in use stoking is performed in the usual manner.

If it is found desirable to increase the draft and allow more air to enter the furnace then the crank handle 39 is manually rotated, so that the vertical grate bars 29 are elevated relatively to the grate bars 28, which constitute the horizontal grate.

Air now passes from the ash pit through the central recessed portion of the grate bars 40 and after passing through the slots 42 in the lateral walls of the said bars the air is delivered to the body of fuel spread on the grate, and thus increases the combustion thereof.

25 It will be readily seen that the guide members 30 are arranged so that the racks 33 cannot become displaced by unmeshing with the pinion 36.

This is accomplished by providing the said guide members with back walls such as are illustrated at 46 in Fig. 5, and it will also be clear that by supporting the guide members 30 from the grate bars 28 constituting the horizontal grate, that the expansion 35 of the said grate bars will be uniform throughout, and thus there is no liability of the vertical grate bars binding and being rendered inoperative.

By adapting this type of grate in a boiler 40 the air delivered to the fuel can be adequately controlled and the best combustion is obtained, and the temperature of the gases

or products of combustion is greatly increased, while the saving in fuel is very great.

45

What I claim as my invention is:

1. A device of the class described comprising a plurality of spaced stationary grate bars, guides located between the grate bars at the ends thereof, a flange on the upper end of each guide designed to overhang and engage the upper face of the said bars, a projection on each guide designed to engage with the under face of the said bars whereby the bar is embraced between the said flange and projection, a spindle extending through the projections of each set of corresponding guides at each end of the bars, pinions mounted on the spindle and located in the guides, a vertical movable grate bar located between pairs of stationary bars and having a central recess and slots through its lateral walls, racks carried by the movable bars meshing with the said pinions, and means for rotating all the pinions whereby the vertical grate bars will be simultaneously elevated.

2. The device claimed in claim 1, in which a bracket extends transversely across the device, a rack mounted in the bracket and movable longitudinally relatively thereto, pinions on all the spindles meshing with the last said rack, means on one of the spindles for manually rotating the spindle whereby the rack will be moved longitudinally to simultaneously rotate all the remaining spindles and elevate the vertical grates, as and for the purpose specified.

In witness whereof I have hereunto set my hand in the presence of two witnesses.
